ABSTRACT OF THE DISCLOSURE

A plaster and mortar mixer including a generally cylindrically shaped mixing drum having a horizontal inlet opening in the top thereof above which is mounted a shaker screen for screening the plaster or mortar prior to mixing. The screen is mounted on rubber supports carried by the mixing drum and is moved in a reciprocal manner above the inlet opening. The reciprocal motion is provided by first and second arms which are normally joined and pivotally mounted to the mixing drum; the first arm having motion imparted thereto by a cam coaxially mounted on the mixing shaft and the second arm being connected to the shaker screen.

BACKGROUND OF THE INVENTION

The present invention relates to apparatus for screening and mixing materials.

Prior to the utilization of certain materials (e.g. sand, cement, plaster, mortar, etc.), it is frequently necessary to screen the material to obtain a uniform size and to remove contaminants such as rocks, leaves and twigs. In large operations, such as in the construction of buildings, a screening plant is commonly utilized to screen the materials prior to the use thereof. Such screening plants are, of course, expensive to construct and operate and, consequently, are economically justifiable only when exceedingly large amounts of material are screened.

However, it is frequently necessary, or at least desirable, to screen a smaller quantity of material than that which is necessary to make the operation of a screening plant practical. In such situations, it has previously been the practice to either (1) not screen at all, (2) screen by hand, or (3) allow the material to work its way through a stationary grid mesh by force of gravity.

None of the above-mentioned practices, however, have been particularly desirable; practices (2) and (3) requiring considerable time and labor to obtain high quality screening. As a result, screening apparatus which is (1) inexpensive to manufacture, and (2) provides efficient high quality screening is commercially desirable.

SUMMARY OF THE INVENTION

The present invention provides a substantially enclosed mixing chamber having a generally central axis and an opening therein suitable for receiving a material to be mixed and for discharging mixed material. A mixing shaft means is rotatably connected to the mixing chamber extending generally coaxially therewith. Screening means (e.g. a wire mesh screen) is positioned overlaying the opening in the mixing chamber and is substantially coextensive therewith. The screen is moved in an agitating manner above the opening to facilitate screening of the material deposited thereon. The agitating motion is provided by reciprocal motion generating means connected to the mixing shaft means; and this reciprocal motion is then imparted to control means which is connected to the screening means. In a preferred embodiment, the operative means comprises a cam and cam follower operatively associated with the mixing shaft. The reciprocal motion is imparted to the screening means by the control means

2

which includes first and second arms normally joined and pivotally connected to the mixing drum for converting the motion imparted thereto by the rotating cam and cam follower to a reciprocal motion for agitating the material deposited on the screen.

The above-described apparatus has numerous advantages. First, it provides an economical and efficient manner of screening materials such as mortar, concrete, sand and the like. Secondly, the drive means (e.g. an electric motor) used to rotate the mixing shaft means is also utilized to impart the reciprocal motion to the material screen. Consequently, an additional motor is not required to operate the screening mechanism. Thirdly, the screen can be mounted on the mixing drum in such a manner so that it can be either removed or swung aside to allow easy cleaning of the drum.

BRIEF DESCRIPTION OF THE DRAWINGS

Referring to the drawings wherein like numerals designate like parts of the invention throughout the figures:

FIG. 1 is a front elevational view of the present invention;

FIG. 2 is a top view of the embodiment shown in FIG. 1 illustrating a quantity of material carried by the screening apparatus of the present invention; and

FIG. 3 is a side elevational view of the embodiment shown in FIG. 1 more fully illustrating the apparatus for agitating the material carried by the screen.

DETAILED DESCRIPTION OF THE PREFERRED EMBODIMENT

In the drawings, screening-mixer apparatus, generally designated 10, is shown as comprising a mixing chamber or drum 12 having a horizontal opening 14 therein in the top thereof above which is positioned a grid mesh or screen 16. Mixing drum 12 has a generally cylindrical bottom and substantially vertical side walls extending upward therefrom to a hinged cover frame or frame 17. The hinged frame 17 has an opening therein substantially coextensive with opening 14 for allowing material which sifts through screen 16 to enter the mixing drum.

Screen 16 is mounted in a rectangularly shaped frame 18 which is generally coextensive with hinged frame 17.

Flexible support means, shown as rubber mounts 19a, 19b, 19c and 19d, are fastened to the four corners of frame 18 and maintain it in a spaced relationship above hinged frame 17. As will be more fully described hereinbelow, the rubber mounts allow screen 16 to be moved in a reciprocal manner above hinged frame 17 and inlet opening 14.

Mixing shaft means shown as a mixing shaft 20 and mixing paddles or blades 21 connected to shaft 20 provide mixing action within drum 12. As illustrated, mixing drum

55 12 is carried by mixing shaft 20 which extends coaxially with the central axis thereof. Shaft 20 extends exterior to mixing drum 12 and is supported by the vertical members 22a and 22b of a frame 22. The vertical members include conventional bearings 24a and 24b (e.g. sealed ball bearings) mounted therein so as to allow mixing shaft 20 to be freely rotatable. Mixing drum 12 includes first and second conventional bearings 25a and 25b, respectively, through which shaft 20 rotatably extends so as to allow drum 12 to remain in an upright position when rotation

60 of shaft 20 occurs. Mixing shaft 20 has a first end thereof connected to a drive means, such as an electric motor (not shown) mounted within a housing 28. When actuated by a clutch mechanism (not shown) mounted within housing 28, the electric motor continuously rotates shaft 20 and blades 21 connected thereto.

An operative means comprising a cam 30 and a cam follower or roller 31 is operatively associated with shaft

20 and a control means illustrated as first and second pivot arms 32 and 34, respectively. As illustrated, cam 30 is coaxially mounted on shaft 20 exterior to drum 12 and near the end of the shaft remote from the electric motor in housing 28. Roller 31 is mounted on a first end of arm 32 in contact with cam 30 so as to move along the lobes thereof upon rotation of the cam. Roller 31 is a conventional sealed roller bearing.

First pivot arm 32 has a first end pivotally connected to a conventional pivoting means 38 (e.g. a hinge) which is rigidly mounted on mixing drum 12 above shaft 20. Second pivot arm 34 includes a first end pivotally connected to a shaker arm 39 which extends substantially horizontally between its attachment to frame 18 and arm 34. A second end of pivot arm 34 is normally joined to a second end of arm 32 and pivotally connected to pivoting means 38. As illustrated, the first and second arms are a unitary structure pivotally connected at their normally joined ends to the hinge 38.

In operation, electric motor in housing 28 is actuated by a clutch lever 40 when mixing is desired. Upon actuation, shaft 20 and blades 21 connected thereto continuously rotate in a clockwise direction with respect to FIG. 3 so as to provide a mixing action within the drum. Mixing drum 12, which is rotatably mounted on shaft 20, remains in the upright position illustrated in FIGS. 1-3 as a result of the clockwise movement of shaft 20 and paddles 21 which causes engagement of a stop element 41 with upright 22b and engagement of a latch bar 42 with stop element 41. The material 50 which is to be mixed within drum 12 is placed on horizontal screen 16 by any number of ways (e.g. by shoveling). As shaft 20 rotates, cam 30 is also caused to rotate imparting a reciprocal vertical movement to first arm 32 as roller 31 moves along the lobes of rotating cam 20. The reciprocal vertical motion of arm 32 imparts a corresponding reciprocal movement to second arm 34 causing the end of arm 34 connected to shaker arm 39 to reciprocally move along a substantially horizontal arc. This reciprocal movement of second arm 34 is then imparted to screen 16 by the pivoted attachment of shaker arm 39 to arm 34 thereby causing shaker arm 39 and frame 18 (in which screen 16 is secured) to move in a sifting or agitating manner as allowed by flexible supports 19a, 19b, 19c and 19d (i.e. a reciprocal horizontal movement with respect to underlying frame 17). This reciprocal agitating motion of screen 16 causes a sifting of material 50 deposited on the screen; the sifted material falling through opening 14 into drum 12 and being mixed therein by rotating blades 21.

When it is desired to empty mixer apparatus 10, latch 42 is released and mixing drum 12 is rotated on shaft 20 by manual force applied to handle 44 so as to allow the mixed material to be exhausted from the mixing chamber through opening 14 and spout 46 by rotation of mixing paddles 21. After the desired amount of mixed material has been exhausted, the mixing drum is returned to its upright position wherein stop element 41 engages upright 22b and is locked in position by latch bar 42; the amount of manual force which must be exerted on handle 44 to return drum 12 to its upright position being reduced by the clockwise rotation of paddles 21.

When it is desirable to clean mixing chamber 12, shaker arm 39 is disconnected from the frame 18. Frame 17 is then rotated on its hinges 50a and 50b, along with screen 16 and frame 18, so that they no longer cover inlet opening 14. With the screening apparatus in this position, mixing chamber 12 can be readily cleaned.

Whereas the present invention has been described in conjunction with one preferred embodiment thereof, it will be readily apparent to those of ordinary skill in the art that changes can be made thereto without departing from the spirit and scope of the present invention.

What is claimed is:

1. Screening-mixer apparatus, comprising:

- (a) a substantially enclosed mixing chamber having a generally central axis;
  - (b) a rotatably mounted, essentially horizontal mixing shaft extending generally coaxially with said central axis of said mixing chamber and having a portion thereof extending horizontally exterior to said mixing chamber, said chamber being carried by said mixing shaft and mounted for rotation thereabout;
  - (c) means defining a substantially horizontal opening positioned in said mixing chamber above said mixing shaft for introducing material into said chamber and for discharging said material therefrom;
  - (d) screening means positioned horizontally above said opening and generally coextensive therewith;
  - (e) means attached to said mixing shaft and rotatable therewith for mixing material introduced into said mixing chamber;
  - (f) means for generating reciprocal motion including a cam mounted on said mixing shaft exterior to said mixing chamber and a cam follower operatively associated with said cam; and
  - (g) control means connecting including first and second rigidly connected cams pivotally mounted on said mixing chamber and having one of said first and second arms connected to said screening means and said cam follower rotatably connected to the other of said first and second arms for imparting an agitating motion to said screening means.
2. The screening-mixer apparatus of claim 1 wherein:
- (a) said cam follower is rotatably connected to said first arm; and
  - (b) said second arm means is connected to said screening means and imparts said agitating motion thereto.
3. The screening-mixer apparatus of claim 1 wherein:
- (a) said opening is substantially rectangular;
  - (b) said screening means includes a rectangular screen frame generally coextensive with said inlet opening and a screen rigidly held by said frame;
  - (c) said agitating motion of said screen frame and screen is a reciprocal motion along a direction substantially parallel to said mixing shaft.
4. The screening-mixer apparatus of claim 3 wherein:
- (a) said first arm is substantially horizontal and includes first and second ends;
  - (b) said cam follower is rotatably mounted on said first end of said first arm; and
  - (c) said second arm is substantially vertical and includes first and second ends, said screen frame being pivotally connected to said first end of said second arm and said second end being rigidly connected to said second end of said first arm.
5. The screening-mixer of claim 4 including flexible support means and a cover frame for said mixing chamber wherein:
- (a) said flexible support means are connected to said screen frame and extend downward to said cover frame for maintaining a space relationship therebetween and for allowing said agitating motion thereof; and
  - (b) said cover frame is pivotally connected to said mixing chamber and includes an opening therein substantially coextensive with said opening in said mixing chamber.
6. Screening-mixer apparatus, comprising:
- (a) a mixing chamber having a generally horizontal central axis and an opening therein suitable for introducing a material into said chamber and discharging said material therefrom;
  - (b) mixing shaft means rotatably connected to said mixing chamber and extending coaxially therewith, said mixing shaft means being adapted for connection to means for imparting rotation thereto;
  - (c) cam means connected to said mixing shaft means and rotatable therewith for generating a reciprocal motion;

(d) screening means overlaying said inlet opening substantially coextensive therewith and mounted for reciprocal motion thereabove; and

(e) arm means connecting said cam means and said screening means for imparting said reciprocal motion to said screening means upon rotation of said cam means. 5

7. The screening-mixer of claim 6 including frame means wherein:

(a) said mixing shaft means is rotatably supported by 10 said frame means so as to allow rotation of said mixing shaft means;

(b) said arm means includes first and second arms pivotally connected to said mixing chamber; and

(c) said cam means includes a cam rigidly connected 15 to said shaft means and a cam follower rotatably

mounted on one of said first and second arms positioned to rotate with said cam upon rotation thereof.
